UNITED STATES PATENT OFFICE.

REUBEN C. BAKER, OF COALINGA, CALIFORNIA, ASSIGNOR TO BAKER CASING SHOE COMPANY, A CORPORATION OF CALIFORNIA.

CASING-SHOE GUIDE.

Application filed March 14, 1923. Serial No. 324,948.

To all whom it may concern:

Be it known that I, REUBEN C. BAKER, a citizen of the United States, residing at Coalinga, county of Fresno, and State of California, have invented new and useful Improvements in Casing-Shoe Guides, of which the following is a specification.

This invention relates to deep well equipment and particularly pertains to a casing 10 shoe guide.

In sinking well casings, it is often necessary to pass the casing shoe and its guide down through a line of pipes or through an open hole which is often drilled through 15 hard substances such as shell or a very hard strata of clay and the like. To protect and guide the casing shoe during the lowering operation, a guide is fitted to the end of the shoe. This guide is generally of a 20 fragile nature and is purposely destroyed after serving its period of usefulness.

It is common practice to secure a guide in the end of a casing shoe by threads and by a frictional connection. These methods 25 have proven unsatisfactory as the former requires considerable time and expense to turn the threads in the casing shoe, especially should the location of the well be such that machine shop facilities are lacking.

30 The second method is also objectionable for the reason that ordinary friction connections do not secure the guide firm enough in the shoe. This is especially true when the guide is employed as a stop for plugs used when pumping liquid cement down 35 into the well to force it around the outside of the casing for the purpose of excluding surface water and strengthening the casing.

Therefore, it is the principal object of 40 the present invention to provide a simply constructed, efficient and inexpensive guide for the purpose described, which may be expeditiously and securely fitted in the end of a casing shoe.

45 The invention contemplates the use of a guide of fragile nature that may be fitted to the end of a casing shoe and which is provided with wedge means that may be expeditiously driven into firm contact with 50 the surface of the shoe after the guide is fitted thereto to firmly maintain the guide in place.

One form which the invention may assume is exemplified in the following descrip-

tion and illustrated by way of example in 55 the accompanying drawings, in which:

Fig. 1 is a vertical section through a well casing and shoe disclosing a guide embodying the invention applied thereto.

Fig. 2 is a view of the guide in side elevation.

Referring more particularly to the accompanying drawings, 10 indicates a well casing, 11 a casing shoe and 12 a hollow guide fixed in the bottom of the casing shoe. 65 This guide is of fragile nature and is formed with a spheroidal body portion 14 formed integral with a sleeve 15 which is intended to be inserted within the bore of the casing shoe. The upper end of the sleeve is inwardly tapered as at 16 forming an annular shoulder 17. The lower portion 70 of the sleeve is perfectly cylindrical so as to snugly fit the bore of the shoe 11.

Fitted around the tapered portion 16 of 75 the sleeve are segmental wedges 17. In the present case there are four wedges. The inner faces of these members are tapered to coincide with the tapered portion 16 of the sleeve as shown in Fig. 1. The outer 80 faces of these wedges are formed with annular serrations 18. To permit the wedges to be driven upwardly when the guide is fitted to the casing shoe, the sleeve is formed with a plurality of apertures 19. A 85 drift pin or bar may be inserted through these apertures to engage the wedges and drive them upwardly to securely wedge the guide in place.

The bottom of the body portion 14 may 90 be closed and plugged, but in the present instance I prefer to use a check valve 20 which is held seated upwardly against the seat of the valve opening 21 by a spring 22. The mounting of this valve will permit the 95 guide to be used as a "floating" plug to relieve part of the burden of the casing when lowering the same through liquid in a well. Also, the valve permits liquid cement to be pumped downwardly through the casing 100 and be forced upwardly around the casing to strengthen the same and prevent seepage of surface water.

In operation, the parts are assembled as shown in Fig. 2 and inserted into the end 105 of the casing shoe. A drift pin may then be inserted through the apertures 19 and driven to force the wedges upwardly. Due to the

coinciding tapered faces of the wedges and sleeve portion 16, internal downward pressure on the guide 12 will tend to increase the holding tendency of the wedges.

5 From the foregoing it is obvious that a comparatively simple efficient and inexpensive shoe guide has been provided that may be tightly secured in the end of a casing shoe.

10 While I have shown the preferred form of my invention, it is to be understood that various changes in the construction of the device may be made without departing from the spirit of the invention as defined in the 15 appended claim.

Having thus described my invention, what I claim and desire to secure by Letters Patent is:—

15 In combination with a well casing, a guide member adapted to be fitted to the end thereof to protect and guide said casing, said guide member comprising a hollow

body portion, a sleeve formed as a continuation of the upper end of said body portion, the upper end of said sleeve being upwardly and outwardly tapered and insertible in the end of the casing, the lower end of said sleeve being of a diameter substantially the same as the largest diameter of said tapered portion whereby a shoulder 20 will be formed between said tapered portion and the remainder of the sleeve, segmented wedges surrounding said tapered portion above said shoulder, said wedges having tapered inner faces coinciding with the taper of said tapered portion of the sleeve, and serrated outer faces engageable with the interior surface of said casing, said sleeve having openings formed therein whereby said wedges may be driven upwardly to firmly hold the guide member in place on the casing.

REUBEN C. BAKER.
